(57) **CLAIM**

The ornamental design for a condiment holder with refuse tray, as shown and described.

DESCRIPTION

FIG. 1 is a perspective view of the condiment holder of the invention showing a number of condiment packages in place in the provided slots, the packages not forming a portion of the invention;

FIG. 2 is a perspective view, similar to FIG. 1, but with the condiment packages removed for ease of illustration;

FIG. 3 is a left side view of the condiment holder of the invention, the right side view being a mirror image thereof; FIG. 4 is a right end view of the condiment holder of FIG. 1;

FIG. 5 is a left end view of the condiment holder of the invention;

FIG. 6 is a top view of the condiment holder of FIG. 1;

FIG. 7 is a bottom view of the condiment holder; and,

FIG. 8 is another perspective view of the condiment holder of the invention, showing the refuse tray in the extended position.
